(57) **CLAIM**

The ornamental design for a portable electronic drumhead, as shown and described.

DESCRIPTION

FIG. 1 is a perspective view of a portable electronic drumhead according to the present invention.

FIG. 2 is a front elevation view thereof, in which a handle-like feature thereof is shown separated from the body of the drumhead for ease of illustration.

FIG. 3 is a rear elevation view thereof, in which a handle-like feature thereof is shown separated from the body of the drumhead for ease of illustration.

FIG. 4 is right side elevation view thereof.

FIG. 5 is left side elevation view thereof.

FIG. 6 is a top plan view thereof, in which a handle-like feature thereof is shown separated from the body of the drumhead for ease of illustration; and,

FIG. 7 is a bottom plan view thereof, in which a handle-like feature thereof is shown separated from the body of the drumhead for ease of illustration.
